UNITED STATES PATENT OFFICE.

NICK H. NEUENS, OF PIERCE, NEBRASKA.

BOILER ATTACHMENT.

1,241,002.

Specification of Letters Patent. Patented Sept. 25, 1917.

Application filed March 10, 1917. Serial No. 154,003.

To all whom it may concern:

Be it known that I, NICK H. NEUENS, a citizen of the United States, and resident of Pierce, in the county of Pierce and State of 5 Nebraska, have invented certain new and useful improvements in Boiler Attachments, of which the following is a specification.

The present invention relates to improvements in attachments for boilers, the object being to produce a simple and effective device whereby jars and other such receptacles may be lowered to the bottom of the boiler while the boiling process is being carried 10 on, and also having means associated therewith permitting the retention of the device above the water allowing the same to drain from the jars.

A still further object of my invention is 15 to provide a device of reticulated or foraminous material permitting the free agitation of the water while boiling.

Other improvements and novel details in the construction and arrangement of the various parts of the apparatus will be brought 20 out more in detail in the description to follow, which, for a clear understanding of the invention, should be considered in connection with the accompanying drawing, 25 forming a part hereof, and wherein is disclosed, for the purpose of illustration, convenient and satisfactory embodiments of the invention. It is to be noted, in this connection, that minor changes in the construction 30 and arrangement of the various parts may be made without departing from the spirit 35 or scope of the invention.

In the drawing:

Figure 1 is a detail sectional view through 40 a receptacle showing my device in elevated position, and

Fig. 2 is a perspective view of my invention, the supporting rods thereof being shown in elevated position.

45 Corresponding and like parts are referred to in the following description and indicated in all the views of the drawing by the same reference characters.

50 My invention is particularly adapted for use with receptacles having bodies of considerable depth.

Referring now more particularly to Fig. 1, a receptacle or boiler designated 10 is of the standard form and provided with the

upper rolled edges 11. The tray member of 55 my invention comprises a sheet metal plate member 12 provided with perforations. The outer edges are rolled as at 13 about a wire strand 14 which provides a reinforcing means. It is to be noted that the roll is 60 provided on the upper face of the tray, thus providing a guarding means to prevent the jars 15 from slipping off the same when the tray member is removed entirely from the receptacle. A pair of apertures are ar- 65 ranged on the tray member adjacent the rolled edge on opposite sides thereof to receive the ends of inverted substantially U-shaped rod members 16. The ends of the rods are bent about the rolled portion of the 70 edges of the tray into engagement with the upper face of the tray member, thus providing means for normally retaining the said rods in an upright position and limiting the inward movement of the same. 75 Looped portions 17 are provided in the arms of the rod members to engage the upper edges of the receptacle and retain the tray in a raised position. While in this position it is obvious that the water is permitted to 80 drain from the jars and the same may readily be removed therefrom. The upper portions of the rod members are provided with straight portions 18 forming handles.

It is to be noted that the ends 19 of the 85 rod members in limiting the inward movement of the same also causes the rods to automatically engage the sides of the receptacle when the same is being lowered or raised, but when it is desired that the tray 90 reach the bottom of the receptacle a slight pressure exerted inwardly on the same will permit the tray to rest on the bottom thereof. I of course do not desire to limit myself to the particular use as set forth as the device may be as readily adapted to be used 95 for many other purposes.

Having thus fully described my invention, what I claim as new and desire to secure by Letters Patent, is:

In a device of the character described, the combination with a receptacle, of a tray member having a plurality of openings therein, the outer edges of said tray being rolled, a pair of resilient inverted substantially U-shaped rods, portions of said rods being bent around the rolled edge of the tray and adapted to pivotally engage the 105

same, looped portions formed midway the upper and lower ends of the U-shaped rods to engage the edges of the receptacle, the ends of said rods forming stops against the tray to limit the inward movement of said rods and to hold resiliently the looped portions thereof in position to engage the upper

edge of the receptacle, and handle portions formed on said U-shaped rods opposite the ends attached to the tray.

In testimony whereof, I affix my signature hereto.

NICK H. NEUENS.
